TREATMENT OF CRACKED HYDROCARBON DISTILLATES WITH A PHENYLENE DIAMINE, OXYGEN, AND ALKALI

Kenneth M. Brown, Hinsdale, Ill., and Charles R. McMahan, Houston, Tex., assignors to Universal Oil Products Company, Des Plaines, Ill., a corporation of Delaware

No Drawing. Application December 29, 1953,
Serial No. 401,074

7 Claims. (Cl. 196—29)

This invention relates to the treatment of cracked hydrocarbon distillates and more particularly to a novel process for effecting both sweetening of sour hydrocarbon distillates and reduction in the gum content thereof.

One method of treating cracked gasoline containing acidic components as, for example, mercaptans, is to subject the gasoline to treatment with caustic solution in order to remove a substantial proportion of the acidic components and then to add a phenylene diamine compound whereby the gasoline becomes sweet in storage. The sweetening is accelerated when effected in the presence of caustic solution. Because the phenylene diamine compound also serves as an oxidation inhibitor, this process is referred to as "inhibitor sweetening." However, it has been found that, with some gasolines, this method of treatment results in the desired sweetening but also results in an excessive increase in the gum content of the gasoline. It now has been found that this increase in gum content is due to the caustic solution utilized during the inhibitor sweetening. The present invention offers a novel method for retaining the improved benefits of inhibitor sweetening and at the same time obtaining reduced gum formation.

In one embodiment the present invention relates to a process for producing a substantially sweet hydrocarbon distillate of reduced gum formation which comprises treating said distillate with caustic solution to remove a major portion of the components which promote gum formation during subsequent sweetening, separating treated distillate from caustic solution, commingling a phenylene diamine inhibitor with the separated distillate, and effecting sweetening thereof in the presence of an oxidizing agent and caustic solution substantially free from impurities promoting gum formation.

In a specific embodiment the present invention relates to a process for producing a substantially sweet cracked gasoline of reduced gum formation, which comprises treating said gasoline with caustic solution to remove a major portion of acidic components from said gasoline, separating treated gasoline from caustic solution, commingling a phenylene diamine inhibitor with the separated gasoline, effecting sweetening thereof in the presence of air and caustic solution substantially free from impurities promoting gum formation, discontinuing the treatment of gasoline when the first mentioned caustic solution becomes saturated with said impurities, withdrawing the thus spent caustic solution and replacing it with the second mentioned caustic solution, and utilizing fresh caustic solution as the second mentioned caustic solution.

The present invention is particularly applicable to the treatment of sour cracked gasoline, including thermally cracked gasoline, catalytically cracked gasoline, reformed gasoline, polyform gasoline, etc., but also may be utilized, with suitable modifications, for the treatment of other gasolines, including substantially saturated gasoline

2

as, for example, straight run gasoline, natural gasoline, etc., when suitably commingled with olefinic or other unsaturated components, and cracked or mixtures of cracked and straight run higher boiling distillates including kerosene, diesel fuel, gas oil, etc.

It will be noted that a hydrocarbon distillate and particularly cracked gasoline is treated with caustic solution to remove a major proportion of the components which promote gum formation during subsequent sweetening. In many uses other acidic components are also removed in this step. The caustic solution generally is utilized as an aqueous solution and may range from about 5° to about 50° Baumé gravity. When the hydrocarbon distillate contains hydrogen sulfide, it preferably is given a pretreatment with caustic solution or otherwise to remove the hydrogen sulfide prior to the treatment to remove mercaptans. These caustic treatments may be batch or continuous type of operations and generally are effected at substantially atmospheric temperature, although subatmospheric or elevated temperature which usually will not be above about 200° F. may be employed.

In accordance with the present invention, the caustic solution utilized for removing the impurities promoting gum formation should be replaced when these impurities appear in the hydrocarbon distillate effluent from this treating step. It is essential that the final sweetening step be effected in the substantial absence of such impurities and, therefore, the impurities should not be included in the hydrocarbon fraction being subjected to the inhibitor sweetening. The use of fresh caustic solution in the inhibitor sweetening step and the proper replacement of the caustic solution in the first treating step generally will result in a final sweetened distillate of reduced gum formation. In some cases, it may be desirable to water wash the distillate from the first caustic treatment in order to insure removal of caustic containing the impurities from the distillate before commingling the inhibitor with the hydrocarbon distillate. In place of water washing, any other suitable treatment to accomplish this may be utilized.

In one embodiment of the invention, when the caustic solution in the first treating step is to be withdrawn, it may be removed from the system and replaced with caustic solution used in the inhibitor sweetening step of the process. Fresh caustic then is utilized in the latter step, and the cycle is repeated as required.

After treatment to remove a substantial proportion of the impurities, the hydrocarbon distillate still will contain a minor proportion of mercaptans, with the result that the distillate is not sweet to the Doctor Test. In accordance with the present invention, a phenylene diamine compound is added to the hydrocarbon distillate, and the inhibitor is contacted with air and fresh caustic solution until the distillate becomes substantially sweet.

Any suitable phenylene diamine compound may be used in accordance with the invention. A preferred phenylene diamine compound comprises N,N'-di-sec-butyl-p-phenylene diamine. Other phenylene diamine compounds include N,N'-di-alkyl-p-phenylene diamines in which the alkyl groups contain from 1 to about 12 carbon atoms per group, including such compounds as N,N'-di-iso-propyl-p-phenylene diamine, N,N'-di-amyl-p-phenylene diamine, N,N'-di-hexyl-p-phenylene diamine, etc. It is understood that the alkyl groups may comprise different radicals as, for example, in such compounds as N-propyl-N'-butyl-p-phenylene diamine, N-butyl-N'-amyl-p-phenylene diamine, N-hexyl-N'-octyl-p-phenylene diamine, etc., and that a mixture of the di-alkyl phenylene diamine compounds may be employed. The phenylene diamine compound may be utilized in a concentration of from about 0.0001% to about 1% by weight and pref-

erably of from about 0.001% to about 0.1% by weight of the hydrocarbon distillate.

Because the inhibitor sweetening reaction comprises the converting of mercaptans to disulfides, presumably through an oxidation reaction, it is essential that air be present in the reaction. Generally sufficient air will be dissolved or entrained in the hydrocarbon distillate in order to satisfy this requirement. However, in other cases sufficient air may not be dissolved in the hydrocarbon distillate, particularly when the hydrocarbon distillate is withdrawn from storage tanks having floating roofs, and in such cases air from an extraneous source must be added to the hydrocarbon distillate. It is understood that oxygen or other oxygen-containing gases may be used in place of air.

The hydrocarbon distillate containing the phenylene diamine compound is allowed to remain in contact with air and caustic solution until the distillate becomes substantially sweet. As hereinbefore set forth, the caustic solution used in the sweetening reaction must be substantially free from impurities promoting gum formation. It has now been found and will be shown in the following examples that the use of caustic solution containing such impurities resulted in sweet gasoline but of excessive gum formation. It generally is necessary to utilize fresh caustic in this step of the process. As hereinbefore set forth, one embodiment of the invention comprises utilizing this caustic to replace the caustic solution used in the first step of the process when the latter is to be removed. When desired other materials which facilitate the inhibitor sweetening reaction may be supplied to this step of the process, provided they do not promote gum formation.

The impurities which promote gum formation have not been definitely established but are believed to include thiophenols, secondary and tertiary mercaptans, etc. Regardless of what these impurities actually are, the use of fresh caustic solution in the sweetening step and the proper replacement of the caustic solution in the first step of the process will avoid the difficulties of excessive gum formation in the treated gasoline.

The sweetening reaction may be effected at substantially atmospheric temperature, which may range from about 50° to about 100° F., or it may be effected at higher temperatures which generally will not be above about 200° F. Usually the sweetening reaction will be effected within 24 hours although, in some cases, a longer time may be required.

The sweetening reaction may be effected in a batch type operation, in which the hydrocarbon distillate, air and phenylene diamine compound are allowed to remain in contact with each other for the desired time, generally some means of mixing being employed including, for example, stirring blades, recirculation of the mixture, etc. In another embodiment, the hydrocarbon fraction may be continuously introduced into the sweetening zone and the distillate continuously withdrawn therefrom, the flow rate being regulated to allow sufficient time of contact in this zone. Here again means for effecting intimate mixing may be provided. It is understood that the final sweetening zone may comprise a conventional storage tank wherein, after sufficient mixing, the caustic is allowed to settle to the bottom of the tank and thereby is separated from the gasoline. In another embodiment, intimate mixing may be obtained by orifice mixers, etc. prior to introduction into the sweetening zone. In some cases, it may be desired to water wash the gasoline after sweetening.

The following examples are introduced to illustrate further the novelty and utility of the present invention but not with the intention of unduly limiting the same.

The gum content of the gasoline was determined by the copper dish method which is a standard method of determining gum in gasoline. According to this method, 100 ml. of gasoline is placed in a copper dish and the

gasoline is evaporated in approximately 3 hours by means of a steam bath and a controlled passage of air over the open top of the dish. The weight of residue in the copper dish is reported as mg. of copper dish gum per 100 ml. of gasoline.

Example I

The gasoline used in this example was polyformed gasoline. When treated with 20° Baumé caustic solution to reduce the mercaptan content of the gasoline to 0.0198% by weight and then stored with about 0.01% by weight of N,N'-di-sec-butyl-p-phenylene diamine for 144 hours, the mercaptan content was reduced to 0.006% by weight but the gasoline had a copper dish gum content of 42 mg. per 100 ml. of gasoline.

Example II

Another sample of the same gasoline was stored in the same manner as described above but the caustic solution used in the inhibitor sweetening step was a fresh solution of 20° Baumé caustic. After 12 hours in storage, the gasoline was sweet and had a copper dish gum content of only 6 mg. per 100 ml. of gasoline. It will be noted that the use of fresh caustic in the inhibitor sweetening step produced both a sweet gasoline and a gasoline of low gum content.

Example III

Another sample of the gasoline was treated in the manner hereinbefore set forth, but the caustic used in the inhibitor sweetening step contained 4% acid oils. This caustic previously had been used for 24 hours to treat the gasoline to remove acidic components. After 48 hours in storage, this gasoline was sweet but had a copper dish gum content of 62 mg. per 100 ml. of gasoline.

We claim as our invention:

1. A process for producing a substantially sweet hydrocarbon distillate of reduced gum formation which comprises treating sour distillate with caustic solution to remove a major portion of components which promote gum formation during subsequent sweetening, separating treated distillate from caustic solution, commingling a phenylene diamine inhibitor with the separated distillate and effecting sweetening thereof in the presence of an oxidizing agent and fresh caustic solution substantially free from impurities promoting gum formation.

2. A process for producing a substantially sweet cracked hydrocarbon distillate of reduced gum formation which comprises treating sour cracked distillate with caustic solution to remove a major portion of components which promote gum formation during subsequent sweetening, separating treated distillate from caustic solution, commingling a phenylene diamine inhibitor with the separated distillate and effecting sweetening thereof in the presence of air and fresh caustic solution.

3. The process of claim 2 further characterized in that said sour distillate is cracked gasoline.

4. The process of claim 1 further characterized in that said sour distillate is polyformed gasoline.

5. The process of claim 2 further characterized in that said phenylene diamine inhibitor is N,N'-di-sec-butyl-p-phenylene diamine.

6. A process for producing a substantially sweet hydrocarbon distillate of reduced gum formation, which comprises treating sour distillate with caustic solution to remove a major portion of components which promote gum formation during subsequent sweetening, separating treated distillate from caustic solution, commingling a phenylene diamine inhibitor with the separated distillate, effecting sweetening thereof in the presence of an oxidizing agent and caustic solution substantially free from impurities promoting gum formation, discontinuing the treatment of the distillate when the first mentioned caustic solution becomes saturated with said impurities, withdrawing the spent caustic solution and replacing it with

the second mentioned caustic solution, and utilizing fresh caustic solution as the second mentioned caustic solution.

7. A process for producing a substantially sweet cracked gasoline of reduced gum formation, which comprises treating sour cracked gasoline with caustic solution to remove a major portion of components which promote gum formation during subsequent sweetening, separating treated gasoline from caustic solution, commingling a phenylene diamine inhibitor with the separated gasoline, effecting sweetening thereof in the presence of air and caustic solution substantially free from impurities promoting gum formation, discontinuing the treatment of

gasoline when the first mentioned caustic solution becomes saturated with said impurities, withdrawing the spent caustic solution and replacing it with the second mentioned caustic solution, and utilizing fresh caustic solution as the second mentioned caustic solution.
